George B. Ingersoll,
ATTORNEY.

UNITED STATES PATENT OFFICE

EMMET P. GRAY, OF DETROIT, MICHIGAN

MUFFLER SUPPORTING DEVICE

Application filed February 27, 1929. Serial No. 343,205.

My invention relates to improvements in a supporting device for mufflers or similar units used in connection with internal combustion engines, and the objects of my improvement are, first, to provide a supporting device having adjustably mounted clamping means; second, to provide a supporting device adapted to allow its supported unit to adjust its position; third, to provide a muffler supporting device capable of deadening vibrations set up within its supported unit; fourth, to provide a supporting device having a minimum of parts; fifth, to provide a supporting device adapted to be manufactured from relatively thin material with a minimum of waste; sixth, to provide a supporting device capable of being applied to its supported member when said supported member is in a vertical, horizontal, or angular position; and seventh, to provide a supporting device having adjustable means capable of being readily removed from its supporting member.

I attain these objects by the mechanism illustrated in the accompanying drawing, in which—

Figure 1 is a side elevation of a muffler supported by my device; Fig. 2, an end view of a muffler supported by my device; Fig. 3, a front elevation of the supporting bracket; Fig. 4, a plan view of the supporting bracket; Fig. 5, a side elevation of the supporting bracket; Fig. 6, a front elevation of the adjustable clamp; Fig. 7, a side elevation of the adjustable clamp; and Fig. 8, a side elevation of a member, in a vertical position, supported by my device.

Similar numerals refer to similar parts throughout the several views.

In Figs. 1 and 2, my device is disclosed as supporting a muffler 1 connected, by the exhaust pipe 2, with an internal combustion engine (not shown). The bracket 3 may be fastened to the frame member 4 by means of the bolts 5 and nuts 6. The bracket 3 may be easily made, if desired, from sheet material, thus lending itself to simple and economical formation. The bracket 3 is provided with a curved seat 7 having a retaining shoulder 8. The retaining shoulder 8 may

be blanked from sheet material in such manner as to result in the notch 9 being formed in the flange 10 of the bracket 3 as each bracket 3 progresses through its blanking and forming die equipment, thus resulting in 55 practically no waste material.

The clamp 11 may be formed of relatively thin sheet or strip material of the desired width to fit on the curved seat 7 of the bracket 3, the clamp 11 being prevented from separating from the bracket 3 by the retaining shoulder 8 and the flange 10. It is to be noted that the clamp 11 is very easily and readily removed from the seat 7 on the bracket 3. This is a distinct advantage for assembling 60 purposes as the bracket 3 may then be permanently fastened to its supporting member such as designated by 4. The clamp 11 is preferably made circular in shape to fit a muffler or member having a circular shape, 65 thus allowing practically any of its length to be placed on the curved seat 7 of the bracket 3. However, it is to be understood that the clamp 3 may be constructed, if desired, with varying shapes, throughout a portion 70 of its length, to facilitate attachment to supported members of varying shapes.

The clamp 11 is provided with extensions or lugs 12, through which pass the clamping bolt 13 which, together with the nut 14, provide means for drawing the clamp 11 tightly around the muffler 1, or any desired member to be supported, thus clamping the muffler 1 against the curved seat 15 of the bracket 3 and, at the same time, drawing the clamp 11 on to the curved seat 7 of the bracket 3. The extensions or lugs 12, of the clamp 11, may have a portion of their open ends 12 folded to provide greater strength to oppose the clamping action of the bolt 13.

In Fig. 8 a muffler or member 16 is disclosed, in a vertical position, and supported therein by my device, said device being attached to the member 17. When used in this manner the brackets 3 are formed with a suitable flange 18 to fit any desired member.

The muffler 1 in Figs. 1 and 2 is of the usual hollow construction and is provided with an outlet member 19 and an inlet member 20, the inlet member 20 being connected

by the exhaust pipe 2 to an internal combustion engine (not shown). The extended use of rubber or flexible mountings for engines when used in motor vehicles or units has resulted in serious damage, in many instances, to the muffler as ordinarily installed therewith. The slight or severe movement of an engine, when secured on a rubber or flexible mounting, tends to cause, through its exhaust member connected with the muffler, a distortion of the muffler from its nominal supported position. This distortion of the muffler tends to crystallize portions of the exhaust member or members connecting the engine with the muffler. This injurious result is prevented by my device allowing the muffler 1 to slightly move in its supported position. This slight movement, of the muffler 1, is accomplished by the clamp 11 and the muffler 1 being seated on the curved seats 7 and 15 of the bracket 3. This slight movement of the muffler 1 can be further made possible by constructing the bracket 3 and clamp 11 of the necessary thickness as to allow slight flexing therein without endangering their tensile or supporting strength. Thus the allowance of movement of the supported muffler or member, by my device, will allow the muffler 1 to be moved slightly by the forces imposed thereon by the engine and the members connecting the engine with the muffler, as said engine and said members move on their flexible supports or mountings.

It is to be further pointed out that any number of clamps 11 and brackets 3 may be used in supporting a desired object or member. This is of distinct advantage if a long object or member, requiring supports at several points throughout its length, is used as thereby the several clamps and brackets may all be alike or similar in size. With the usual muffler clamp as fastened around the inlet member 20 and the outlet member 19, when it is desired to add support devices at various intervals, a greater number of different clamps and brackets will be required than would be necessary when my supporting device is used as the number of supporting devices at various points may be increased as desired without introducing new sizes and shapes, this being due to my supporting device attaching to the uniform outside diameter of the muffler or member to be supported.

Another distinct advantage of my supporting device is apparent when supporting hollow mufflers or members connected with an engine in motor vehicles or units. The operation of the motor will set up vibrations, with consequent objectionable resonance sounds, in hollow mufflers or members and my supporting device will deaden and eliminate such objectionable resonance sounds. This is accomplished by the clamp 11 circumferentially compressing and binding the hollow body of

the muffler or member at a point or points within its length.

It is to be further understood that my supporting device is not restricted to mufflers and similar members but its use may be easily extended to a variety of units to be supported, without departing from the spirit of my invention.

I claim:

1. In a supporting device, the combination of a bracket provided with a circular wall portion adapted to contact a circular member to be supported by said bracket, said bracket being provided with a pair of flanges oppositely disposed about the circular wall portion of said bracket, one only of said flanges of said bracket being provided with openings for attaching purposes, the other flange of said bracket having a lesser length than said flange provided with openings for attaching purposes, and a clamping member surrounding the circular wall portion of said bracket together with the circular member to be supported, said clamping member being adapted to be moved only over said flange of lesser length when said bracket is in its attached position, the assembly of said clamping member being thereby facilitated.

2. In a supporting device, the combination of a bracket provided with a circular wall portion adapted to contact a circular member to be supported by said bracket, said bracket being provided with a pair of flanges oppositely disposed about the circular wall portion of said bracket, said pair of flanges being further oppositely disposed, relative to the circular wall portion of said bracket, from the circular member to be supported, one only of said pair of flanges being provided with openings for attaching said bracket, and a clamping member surrounding the circular wall portion of said bracket together with the circular member to be supported, said clamping member being located adjacent the outer end of one of the pair of flanges of said bracket.
